RAZOR BLADE HANDLE

Emmet H. Morrow, Chicago, Ill.

Application May 16, 1941, Serial No. 393,707

15 Claims. (Cl. 30—85)

The present invention relates to safety razors and more particularly to certain improvements in construction and operation thereof.

Heretofore, safety razors, particularly of the "Gillette" and other similar types, have consisted of a clamping plate or blade holder, a guard plate, and a solid handle having an internally threaded recess at one end for receiving a threaded stud carried by the blade holder and passing through the guard plate for clamping the latter between the blade holder and the one end of the handle. A user of such a safety razor adjusts the angle at which the blade engages the skin surface to be shaved by deflecting the wrist and rotates the blade to follow the contour of the skin surface by rolling the handle between the fingers.

This manner of manipulating the razor has been necessary due to the rigid connection of the various parts. As the skin surfaces to be shaved, particularly the face and the neck, include many curves, ridges and indentations, the angle at which the razor blade is rotated to slide along one surface portion may be such as to cause engagement at a corner only thereof on an adjacent surface. This causes cutting or gouging of the skin which often results in serious infections.

In addition, the pressure exerted by hand manipulation of these rigid razor constructions is usually so great, in trying to maintain contact between the entire length of the razor blade cutting edge and the skin surface to effect a clean shave, that small skin protuberances and imperfections are usually sheared off.

It is, therefore, an object of the present invention to provide a safety razor in which the blade is rotatable to maintain full cutting edge engagement with the skin surface to be shaved without rolling of the handle by the user.

Another object of the present invention is to provide a razor in which the parts are assembled in the usual manner with the blade and its clamping parts being selectively held rigidly or rotatably connected to the handle thereof.

Still another object of this invention is to provide a jointed handle construction for a safety razor which may be locked to provide a rigid construction or unlocked to permit the mounted blade to rotate relative to the handle.

A further object of this invention is to provide a razor of simple and durable construction having a minimum number of parts which may be quickly and easily assembled and disassembled.

Generally, the razor construction of this invention includes the usual blade holder or clamping plate, a guard plate and a handle. The

handle differs from the usual construction by providing an intermediate joint which is selectively locked or unlocked for effecting a rigid handle or one in which the portions of the handle are free for relative rotation.

The novel features believed to be characteristic of the present invention are set forth with particularity in the appended claims. The invention itself, however, both as to its organization and manner of construction, together with further objects and advantages thereof, may best be understood by reference to the following description taken in connection with the accompanying drawing, in which:

15 Figure 1 is a view in side elevation of a razor construction embodying features of one form of this invention;

20 Figure 2 is a plan view of the device shown in Fig. 1 and illustrating, in dotted lines, the degree of free angular rotation of the razor head on its handle;

25 Figure 3 is an enlarged fragmentary vertical cross-sectional view, with parts in elevation, of the razor handle illustrated in Fig. 1 as seen when taken substantially in the plane indicated by the line III—III and illustrating the handle parts in free rotatable relation;

30 Figure 4 is a view similar to Fig. 3 illustrating the handle parts held in non-rotatable relation;

35 Figure 5 is a view similar to Fig. 3 illustrating another form of a handle construction for a razor; and,

Figure 6 is an enlarged transverse cross-sectional view, with parts in elevation, as seen when taken substantially in the plane indicated by the line VI—VI of Fig. 5.

Figure 7 is an elevation of a modified form of the invention.

40 The razor construction 10 illustrated in Figure 1 generally includes a blade holding head 11, for clamping a razor blade 12 in place, and a handle 13 which is removably connected to the blade holding head.

45 The blade holding head 11 has a clamping plate 14 with a threaded locking stud 15 extending away from the inner face thereof at a position substantially at its center. A guard plate 16 is arcuate in shape and has a central aperture therethrough for receiving the threaded locking stud 15. This construction is the same as that of the well-known "Gillette" type in which the handle is provided with an interiorly threaded end recess for engagement with the threaded locking stud 15 by which the flexible razor blade 12

is arcuately clamped between the clamping plate 14 and the guard plate 16.

The handle 13 of the razor construction of the present invention differs over the usual handle construction by the provision of jointed parts which may be selectively locked or unlocked as desired.

As best shown in Figure 3, the handle 13 has an upper handle portion 17 with an interiorly threaded recess at one end thereof (not shown) and a rod-like portion 18 at its lower end. A circumferentially extending peripheral slot 19 is provided intermediate the ends of the rod-like portion 18. An inverted U-shaped slot 20 is provided in the rod-like portion 18 above the peripheral slot 19 with one leg 21 of the U slot terminating in the peripheral slot 19 and its other leg 22 terminating in spaced relation from the peripheral slot 19.

A cup-shaped sleeve 23, having its lower end 24 closed, slidably embraces the rod-like portion 18. A small cap screw 25 has a threaded shank 26 inserted through a side wall of the sleeve 23 with an inner end 27 thereof seating normally in the peripheral slot 19 to slide freely therein. If desired, a pin or other similar member may be substituted for the cap screw 25. It is preferred, however, that a cap screw be used so that the parts may be easily disassembled.

The lower end of the handle portion 17 is provided with a reduced portion 28 for positioning one end of a coil spring 29, the other end of which is seated against the end wall 24 of the sleeve 23. The knob 23 illustrated in Figure 3 tapers inwardly to seatingly receive therearound the end coil of the spring 29. Compression of the coil spring 29 normally maintains the slot engaging end 27 of the cap screw 25 against the lower side 30 of the peripheral slot 19. This frictional engagement permits the sleeve 23 to be rotated around the upper handle portion 17 and serves as a frictional brake so that the rotation is not too free as to interfere with proper shaving operations.

If it is desired to lock the sleeve 23 on the upper handle portion 17, the sleeve is rotated to a position in which the cap screw 25 is in alignment with the leg 21 of the slot 20. The sleeve 23 is then forced upwardly against compression of the spring 29 whereby the slot engaging end 27 of the cap screw slides along the slot leg 21. When the inner end of the cap screw engages with the end of the slot leg 21, the sleeve 23 is rotated to the right to slide the end of the cap screw through the slot portion 21. When the inner end of the cap screw 25 has been turned to a position in alignment with the short slot leg 22, compression of the spring 29 urges the sleeve member 23 away from the upper handle portion 17 until the cap screw engages with the end of the slot leg 22. The parts are then positioned as illustrated in Figure 4. The sleeve 23 is thereby held against rotation on the upper handle portion 17. These parts may be unlocked to provide free relative rotation therebetween by sliding the slot engaging end 27 of the cap screw 25 through the slot 20 and into the peripheral slot 19.

The handle parts are rigidly connected to each other as shown in Figure 4 for the purpose of threading the upper handle part 17 to the threaded locking stud 15 when the razor is to be assembled or disassembled. After the parts are assembled, they are turned to the relative posi-

tions illustrated in Figure 3 whereby the sleeve 23 is freely rotatable on the upper handle portion 17.

Inasmuch as the skin surfaces to be shaved, particularly the face and the neck, include many curves, ridges and indentations, it is necessary for the user of a safety razor to continually roll the handle thereof between his fingers in order that the entire length of the razor blade be maintained in contact with the skin surface. In so doing, the user usually presses the razor against the skin surface with a much greater force than is either necessary or conducive to good results. Often, this excess pressure is the cause of shearing slight protuberances or imperfections from the skin being shaved. In addition, the force exerted on the razor tends to force the skin to assume the angle at which the blade holding head is held as the razor is drawn over the skin surface. In cases where the skin is tightly drawn over the underlying bone structure or where the skin has lost its pliant characteristics due to age or other reasons, it will not flex with the angularly held blade holding head and will oftentimes result in a corner of the blade scratching or gouging the skin surface.

By providing a handle of the type herein described and illustrated, the blade holding head is free for rotation relative to the handle portion which is grasped by a user. Consequently, the user need only flex his wrist to a position in which the razor blade is held at an angle to the face which has been found to give the best shave. Any rotation of the blade holding head necessary to keep the entire cutting edge of the blade in contact with the skin surface will automatically be effected by merely drawing the razor over the skin surface to be shaved. As a result, less pressure need be exerted by the user and a better shave is effected without irritation of the skin surface.

As shown in Figure 7, the sleeve 23 need not be in axial alignment along its entire length with the longitudinal axis of the upper handle portion 17. The lower portion of the sleeve 23 may be curved or angularly offset as at 32 to provide the proper shaving angle when the handle is held by the user without any wrist deflection. In the handle construction illustrated in Figure 7, it is only necessary that the lower sleeve portion be angularly offset at a distance below the rod-like portion 18 to permit relative axial movement between the sleeve and the upper handle portion 17 when the parts are moved into locked or unlocked positions.

Likewise, the threaded locking stud 15 may be angularly disposed relative to the blade clamping plane of the plate 14 for the purpose of offsetting the handle 13 to effect the desired shaving angle.

Obviously, it is not necessary in shaving operations that the blade holding head 11 be mounted on the handle 13 in such a manner that rotation of 360° therebetween is effected. For all practical purposes this rotation may be confined to a maximum of approximately 30° as shown in the full and dotted line illustrations in Figure 2. The razor handle construction illustrated in Figures 5 and 6 provides for such a limited rotation between the blade holding head 11 and the handle 13. In this construction, the upper handle portion 34 is provided with an intermediate circular portion 35 of reduced diameter. The end 36 extending downwardly from the intermediate portion 35 is of the same diameter thereof but is

of semi-circular shape as best shown in Figure 6. A threaded stud 37 is either connected to or integrally formed at the end of the semi-circular portion 36 for a purpose to be explained later.

A rotatable sleeve 38 slidably embraces the reduced portion 35 and the semi-circular portion 36 and abuts against the shoulder 39 formed by the reduced portion 35. A retaining nut 40 is threaded to the stud 37 and against the end of the semi-circular portion 36. The sleeve 38 is of slightly less length than the combined portions 35 and 36 in order that it may freely rotate after the retaining nut 40 abuts against the end of the semi-circular portion 36.

A transversely extending slot 41 is provided in the semi-circular portion 36 adjacent the reduced portion 35. A flat spring member 42 has one end 43 connected to the inner periphery of the sleeve 38 by means of a screw 44. It is to be understood, however, that this connection may be made by a rivet, welding or any other suitable means. The other end of the spring member 42 is angularly offset to provide a flange 45 positioned in alignment with the slot 41. Obviously, if the spring flange 45 is seated within the slot 41 and held therein under pressure, little or no rotation of the sleeve 38 relative to the upper handle portion 34 is possible. If the spring member 42 is permitted of its own record to seat along its entire length against the inner periphery of the sleeve 38, then rotation of the sleeve is possible between limits in which the slot 41 engages the corners of the spring flange 45. The corners 45a and 45b of the spring flange 45 are rounded and separated by a curved end recess 46. The curved corners thereby provide spaced spring cams engageable within the slot 41.

The adjustment of the spring member 42 toward and away from the slot 41 is provided by a screw 47 extending through a side wall of the sleeve 38 into engagement with an intermediate portion of the spring member. By threading the length of the shank of the screw 47 inwardly, the handle parts are locked against rotation. When the screw 47 is threaded outwardly to a position in which the spring member lies against the inner periphery of the sleeve 38, maximum rotation of approximately 30° is permitted by the blade holding head and its connected upper handle portion 34 relative to the sleeve 38. The screw 47 may be threaded inwardly between these maximum positions whereby the relative rotation of the razor parts is to any desired degree.

Should the screw 47 be removed, rotation of the blade holding head will be resiliently opposed by the unsupported length of the spring member and consequently the head will always be returned to its normal position when the razor is not in use.

If the spring member 42 and the screws 44 and 47 are removed, the sleeve 38 is free for complete rotation about the axis of the upper handle portion 34.

It will be apparent from the foregoing that I have provided a handle construction for a razor which is selectively operable by a user to permit free rotation of the blade holding head relative to the handle portion gripped by a user to practically any desired degree.

While particular embodiments only of this invention have been illustrated, it will, of course, be understood that the invention should not be limited thereto, since many modifications may be made and, therefore, it is contemplated by the

appended claims to cover all such modifications as fall within the true spirit and scope of the present invention.

I claim as my invention:

- 5 1. In a razor having a blade holding head, a first handle portion removably connected to said head, a second handle portion, and means connecting said handle portions together for relative movement or for fixed engagement therebetween at the will of the operator.
- 10 2. In a razor having a blade holding head, a handle having interengaging portions, one of said portions being removably connected to said head, and means selectively operable for connecting said handle portions together for relative movement or for fixed engagement therebetween at the will of the operator.
- 15 3. In a razor having a blade holding head, a handle having interengaging portions, one of said portions being removably connected to said head, and means selectively operable for affording relative axial and rotative movements between said handle portions and for locking said portions against relative movement when said handles are interengaged in extended position.
- 20 4. In a razor having a blade holding head, a handle portion removably connected to said head, a tubular handle portion slidably embracing said first handle portion, and interengaging means on said handle portions selectively operable for connecting said handle portions for relative rotative movements and in fixed engagement when said slidably embracing portion is in relatively extended position.
- 25 5. In a razor having a blade holding head, a handle portion removably connected to said head and having a slot therein, a tubular handle portion slidably embracing said first handle portion, and adjustable means on said tubular handle portion for engaging the slot in said first handle portion for connecting the handle portions for axial and rotative movements therebetween and for locking them together in fixed engagement.
- 30 6. A handle for a razor having a blade holding head, comprising a member adapted at one end for removable connection to said head and having a slot in an intermediate portion thereof, a tubular member slidably embracing said first member, and an adjustable member carried by said tubular member and movable into and out of said slot for connecting said first member and tubular member for relative axial and rotative movements therebetween and for locking them together in fixed engagement.
- 35 7. A handle for a razor having a blade holding head, comprising a member adapted at one end for removable connection to said head and having a slot adjacent the other end thereof, a tubular member slidably embracing said first member, a pin carried by said tubular member and seated in said slot, and spring means between said members normally urging them in opposite directions.
- 40 8. A handle for a razor having a blade holding head, comprising a member adapted at one end for removable connection to said head and having a slot adjacent the other end thereof, said slot having a portion extending peripherally around said member and an inverted U-shaped portion spaced from said peripheral portion, one leg of said U-shaped slot portion being spaced from the peripheral slot portion and its other leg extending into said peripheral slot portion, a tubular member closed at one end and slidably
- 45 9. A handle for a razor having a blade holding head, comprising a member adapted at one end for removable connection to said head and having a slot adjacent the other end thereof, said slot having a portion extending peripherally around said member and an inverted U-shaped portion spaced from said peripheral portion, one leg of said U-shaped slot portion being spaced from the peripheral slot portion and its other leg extending into said peripheral slot portion, a tubular member closed at one end and slidably
- 50 10. A handle for a razor having a blade holding head, comprising a member adapted at one end for removable connection to said head and having a slot adjacent the other end thereof, said slot having a portion extending peripherally around said member and an inverted U-shaped portion spaced from said peripheral portion, one leg of said U-shaped slot portion being spaced from the peripheral slot portion and its other leg extending into said peripheral slot portion, a tubular member closed at one end and slidably
- 55 11. A handle for a razor having a blade holding head, comprising a member adapted at one end for removable connection to said head and having a slot adjacent the other end thereof, said slot having a portion extending peripherally around said member and an inverted U-shaped portion spaced from said peripheral portion, one leg of said U-shaped slot portion being spaced from the peripheral slot portion and its other leg extending into said peripheral slot portion, a tubular member closed at one end and slidably
- 60 12. A handle for a razor having a blade holding head, comprising a member adapted at one end for removable connection to said head and having a slot adjacent the other end thereof, said slot having a portion extending peripherally around said member and an inverted U-shaped portion spaced from said peripheral portion, one leg of said U-shaped slot portion being spaced from the peripheral slot portion and its other leg extending into said peripheral slot portion, a tubular member closed at one end and slidably
- 65 13. A handle for a razor having a blade holding head, comprising a member adapted at one end for removable connection to said head and having a slot adjacent the other end thereof, said slot having a portion extending peripherally around said member and an inverted U-shaped portion spaced from said peripheral portion, one leg of said U-shaped slot portion being spaced from the peripheral slot portion and its other leg extending into said peripheral slot portion, a tubular member closed at one end and slidably
- 70 14. A handle for a razor having a blade holding head, comprising a member adapted at one end for removable connection to said head and having a slot adjacent the other end thereof, said slot having a portion extending peripherally around said member and an inverted U-shaped portion spaced from said peripheral portion, one leg of said U-shaped slot portion being spaced from the peripheral slot portion and its other leg extending into said peripheral slot portion, a tubular member closed at one end and slidably
- 75 15. A handle for a razor having a blade holding head, comprising a member adapted at one end for removable connection to said head and having a slot adjacent the other end thereof, said slot having a portion extending peripherally around said member and an inverted U-shaped portion spaced from said peripheral portion, one leg of said U-shaped slot portion being spaced from the peripheral slot portion and its other leg extending into said peripheral slot portion, a tubular member closed at one end and slidably

embracing said first member, a screw carried by said tubular member and seated in said slot, and a coil spring in said tubular member having one end seated on the closed end of the tubular member and its other end seated against said first member, said pin when seated in said peripheral slot portion permitting free relative rotation between said members and when seated in said one leg of the U-shaped slot portion holding said members against relative rotation.

9. A handle for a razor having a blade holding head, comprising a member adapted at one end for removable connection to said head and having a threaded stud at its other end, a sleeve rotatably seated on an intermediate portion of said member, and a member threaded to said stud for retaining said sleeve on said first member.

10. A handle for a razor having a blade holding head, comprising a member adapted for removable connection to said head and having a semi-circular portion, a sleeve rotatably mounted on said semi-circular portion, and means between said sleeve and semi-circular portion for limiting said rotation of the sleeve.

11. A handle for a blade holding head, comprising a member connected to said head and having a reduced portion of segmental circular cross-section, a sleeve rotatable on said reduced portion, and spring means between said reduced portion and said sleeve for resiliently opposing relative rotation of said member and sleeve.

12. A handle for a razor having a blade holding head, comprising a member adapted at one end for removable connection to said head and having a reduced semi-circular portion terminating in a threaded stud, a sleeve rotatably mounted on said semi-circular portion, a nut member threaded to said stud against said semi-circular portion, and adjustable spring means carried by 40

said sleeve and engageable with said semi-circular portions for limiting the rotation of said sleeve.

13. A handle for a razor having a blade holding head, comprising a member having at one end a threaded recess for removable connection to said head and a transversely slotted reduced semi-circular portion terminating in a threaded stud, a sleeve rotatably mounted on said semi-circular portion, a nut member threaded to said stud against said semi-circular portion, a spring member having an offset flange portion at one end with extending corners and being connected at its other end to said sleeve, and a threaded member carried by said sleeve and engaging said spring member for adjustably moving it toward and away from said semi-circular portion, said flange portion on the spring member being movable into and out of engagement with the slot in said semi-circular portion for limiting the rotation of said sleeve.

14. In a razor having a blade holding head, a handle extending angularly away from said head for positioning the clamped razor blade at a desired shaving angle, and means on said handle selectively controllable for maintaining the head rotatable relative thereto or fixed relative thereto.

15. In a razor, the combination of a blade retaining head, a first handle section secured to the head, a second handle section secured to said first section, connecting mechanism between said sections including interlocking means on each of said sections, said interlocking means being constructed and arranged to retain the sections against axial separation and for relative rotation and including means for locking said connecting mechanism in rigid relationship at the will of the operator.

EMMET H. MORROW.
